UNITED STATES PATENT OFFICE

KENNETH L. OZMUN, OF CHICAGO, ILLINOIS, ASSIGNOR TO CHICAGO CARDBOARD COMPANY, OF CHICAGO, ILLINOIS

METHOD OF DISPLAY MOUNTING

Application filed October 26, 1931. Serial No. 571,153.

This invention relates in general to the method of mounting printed or lithographed sheets upon a cardboard or other mounting, and has more particular reference to display mounting of this kind in which an opening or cut-out is provided in the main supporting board through which a light may shine to illuminate a portion of the display making it more attractive and distinctive.

- 10 One of the principal objects of the invention is in the provision of a novel method of applying a lithographed sheet to the display board simultaneously for preventing it from warping or buckling.
- 15 Another object of the invention is in the provision of a display mounting in which the lining sheet and printed sheet are applied simultaneously to a board having a cut-out, and thereafter removing the lining sheet by 20 die cutting.

A further object of the invention is in the method of preparing a mounting board by removing the lining sheet at the back of a cut-out portion by means of a die of the same 25 size or slightly larger than the actual cut-out, the lining sheet within the cut-out then being torn from the back of the display board.

Other objects of the invention will appear 30 hereinafter, the accompanying drawing illustrating more or less diagrammatically the method for carrying out the invention.

In the drawing, Fig. 1 represents a cutting die applied to a display board for cutting it;

35 Fig. 2 is a face view of a display board with a cut-out design in it;

Fig. 3 is a diagrammatic view illustrating a cut-out board as it passes about the paste 40 through paste appliers for both sides of the board and to receive sheets on both sides of the board;

Fig. 4 is a sectional detail view illustrating the application of a cutting die to one side of 45 a coated display board and about to cut-out one of the facing sheets;

Fig. 5 is a fragmentary view showing the display board with a portion of one of the lining sheets removed at the cut-out; and

50 Fig. 6 is a sectional fragmentary view

showing the torn edge of the cut-away facing sheet.

In general the method of mounting the board is first to die cut the cardboard with any desired design, then to mount the cardboard with paper by applying simultaneously two sheets at the opposite sides of the board over the opening, the paste being applied only to the board, so that it is not applied to the mounting sheets at the cut-out portion, and then to cut out one of the mounting sheets with the same die which makes the opening in the board, or with a die slightly larger than the opening, so that the paper at one face of the board may be removed, leaving only the other face sheet extending over the opening.

Referring now more particularly to the drawing and to the method of carrying out the invention, a board 10 of thick paper or cardboard is first thoroughly pressed, dried and rolled to remove all surplus moisture and any desired cut-out design 11 is formed by means of a die 12, the opening or cut-out being entirely through the board.

The board with the cut-out is then passed between upper and lower pasters 13 and 14 having paste applying rollers 15 and 16 which engage the opposite faces of the board, applying the paste equally to the faces of the board so that it is equally moistened on both sides. To the paste covered board are then simultaneously applied lining and lithographed sheets 17 and 18 which are represented as being applied by rollers 19 and 20 respectively. These sheets are smoothly pressed against the opposite pasted surfaces of the board and the paste is not applied to the coating sheets so that in the cut-out portions the cover sheets are not pasted.

After the cover sheets are firmly attached, by the paste, either by drying or by allowing them to set and harden on the board, the covered board is again applied to a cut-out die 21 having the same or a different design than the original cut-out die. In some cases the original die may be used, but in other instances it is desirable to have the cut-out die slightly larger than that which made the original design so that the cutting edge will

over-lap the cut edge of the board, as shown more clearly in Figure 4. This cut-out die 21 is applied only to extend through the cover sheet at one side of the board so that the portion within the die and extending over the cut-out 11 is removed about the edge or edges thereof. In tearing away the cover sheet 17 from the board 10 the edge 22 may be irregularly torn as illustrated in Figures 5 and 6 and the edge of the board 10 surrounding the cut-out opening 11 may also be partially torn away at the edge 23 of the opening as also shown in Figure 6. This tearing however is not sufficient to destroy the cut-out opening 11 and when the lining sheet is removed, the other cover sheet 18, usually the outside sheet which bears the printing or lithographing, is unbroken and when there is no strong light behind the board 10 the display looks like any ordinary mounted display sheet. When a strong light or a flasher is positioned behind the board the cut-out portion of the board will appear to be illuminated, thus forming an attractive display which draws attention to the display and particularly to the illuminated part.

In first drying the cardboard sheet to which the mounting sheets are applied, it is dried beyond or less than its normal humidity so that it will not be too wet when paste is applied to both sides thereof.

By applying the paste and the opposite cover sheets at the same time, the cardboard dries evenly on both sides, thus reducing the tendency to warp or buckle.

The natural shrinkage of the cover sheets and the cardboard when the paste is dry or set, causes the cover sheet which is retained over the cut-out or opening, to be drawn taut and smooth, and when viewed from the front with no stronger light behind it, it presents the appearance of any flat printed or ornamental display, which may be varied, as for night use, by placing a light behind the cut-out.

I claim:

1. The method of display cardboard mounting which comprises drying the cardboard to less than its normal humidity, in simultaneously pasting a face and a lining sheet to opposite sides of the cardboard, thereby preventing the board from warping when the paste is dry.

2. A method of cardboard mounting which comprises drying the cardboard beyond its normal humidity, applying paste to the opposite sides of the cardboard, and then applying cover sheets to opposite sides of the pasted cardboard so that the paste when dry will not warp or buckle the cardboard.

3. The method of mounting cardboard displays having perforations therein which consists in drying the cardboard beyond its normal humidity, in pasting cover sheets on the

opposite faces of the cardboard covering the perforations, the drying of the cover sheets and the expansion of the cardboard drawing the cover sheets tautly and smoothly over the perforations.

4. A method of mounting cardboard displays having perforations therethrough which comprises applying paste to the faces of the cardboard, in applying front and lining sheets to the opposite pasted faces of the cardboard, and in removing the lining sheet at the perforations.

5. The method of mounting a perforated cardboard display which consists in simultaneously applying paste to the opposite faces of the cardboard, in applying cover sheets to the opposite pasted faces and in removing the cover sheet over the opening at one side of the cardboard.

6. The method of mounting a perforated cardboard display sheet which consists in simultaneously applying paste to the opposite faces of the cardboard, in simultaneously applying cover sheets to the opposite pasted faces of the cardboard, and in removing the cover sheet from over the perforation at one side of the board after the paste sets.

7. The method of mounting cardboard display sheets which consists in perforating the cardboard, in applying paste to the opposite sides thereof, in attaching cover sheets to the pasted sides and in removing the cover sheet from the opening at one side of the cardboard.

8. The method of mounting cardboard display sheets which consists in die-cutting an opening through the cardboard, in pasting cover sheets on opposite faces of the cardboard over the opening and in die-cutting a cover sheet to remove it from one side of the board.

9. The method of mounting cardboard display sheets which consists in die-cutting an opening of desired shape in the board, in pasting cover sheets on opposite faces of the board over the opening and in removing the cover sheet on one side of the board by means of the same die or one slightly larger and of the same shape as the opening.

10. The method of mounting a perforated cardboard display which consists in pasting cover sheets on opposite sides of the board and over the perforation and in then die-cutting the cover sheet at one side of the opening into the edge of the cardboard so that this cover sheet can be removed from the opening.

11. The method of mounting a cardboard display sheet which consists in thoroughly drying the cardboard, in die-cutting an opening of the desired shape therein, in simultaneously applying paste to the opposite faces of the perforated cardboard, in simultaneously applying cover sheets to the paste covered sides of the board, in drying the cover sheets

on the board, in die-cutting the cover sheet at one side of the opening from the cardboard with a larger or the same die with which the cardboard was cut and in removing the cut-out portion of the cover sheet 5 over the opening leaving the other cover sheet stretched tightly over the opening.
